CLAIM

The ornamental design for a two-piece clamp assembly as shown and described.

DESCRIPTION

FIG. 1 is a perspective top front right view of a two-piece clamp assembly, illustrating a first clamp feature and a second clamp feature, showing my new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines herein represent boundaries of the claimed invention and form no part of the claimed invention.
